(57) **CLAIM**

We claim the ornamental design for a cosmetic applicator, as shown and described.

DESCRIPTION

FIG. 1 is a top perspective view of a cosmetic applicator showing our new design;
FIG. 2 is a rear perspective view thereof;
FIG. 3 is a side elevational view thereof;
FIG. 4 is a front elevational view thereof;
FIG. 5 is a top plan view thereof; and,
FIG. 6 is a bottom plan view thereof.
The broken lines immediately adjacent the shaded areas represent the bounds of the claim and all other broken lines are for illustrative purposes only. None of the broken lines form a part of the claimed design.
